TACK DRIVING MACHINE.

No. 360,147.

Patented Mar. 29, 1887.

UNITED STATES PATENT OFFICE.

MARTIN R. ETHRIDGE AND FRANK N. ETHRIDGE, OF LYNN, MASSACHUSETTS;
SAID FRANK N. ETHRIDGE ASSIGNOR TO SAID MARTIN R. ETHRIDGE.

TACK-DRIVING MACHINE.

SPECIFICATION forming part of Letters Patent No. 360,147, dated March 29, 1887.

Application filed December 24, 1886. Serial No. 222,439. (No model.)

To all whom it may concern:

Be it known that we, MARTIN R. ETHRIDGE and FRANK N. ETHRIDGE, citizens of the United States, residing at Lynn, in the county 5 of Essex and State of Massachusetts, have invented certain new and useful Improvements in Tack-Driving Machines; and we do hereby declare the following to be a full, clear, and exact description of the invention, such as will 10 enable others skilled in the art to which it app- pertains to make and use the same.

This invention relates to improvements in tack-driving machines; and it consists in the construction, arrangement, and combination 15 of parts, substantially as will be hereinafter described and claimed.

In the annexed drawings, illustrating our invention, Figure 1 is a perspective view of the entire machine, together with a filling at- 20 tachment for supplying the raceway. Fig. 2 is a vertical section of the same, taken in a vertical plane passing through the line xx of Fig. 1. Fig. 3 is a horizontal sectional plan view on the line yy of Fig. 2. Fig. 4 is a top 25 plan of the parts included between the lines v and w of Fig. 2. Fig. 5 is a vertical section of the device for filling the raceway, taken on the line z of Fig. 1. Fig. 6 is a detail sectional elevation of the mechanism for transferring the 30 tacks from the raceway to the plunger-barrel, and shows the rotative tack-carrier in the position which it occupies when receiving a tack from the raceway. Fig. 7 is a similar view, and shows the position of the rotative tack- 35 carrier when depositing a tack in the plunger-barrel. Fig. 8 is a sectional detail plan of the notched plate which forms a part of the horizontally-rotative tack-shifter.

Similar letters of reference denote corre- 40 sponding parts throughout all the figures.

In the general and ordinary use of our im- proved tack-driving machine the operative parts thereof are actuated by power communi- 45 cated from a distance, and, consequently, the main frame, which supports the mechanical devices, is arranged similarly to other sus- pended nailing-machines, so as to swing above the table or bench before which the artisan is stationed, and thus be conveniently moved by 50 him from point to point of the work.

A represents a skeleton frame provided at

its topmost end with a hook, a , which engages a chain, whereby the said frame, as well as the rest of the machine, is supported. Below the frame A, and firmly secured thereto, is a me- 55 tallic casting, B, which serves as a portion of the plunger-barrel, and below the casting B, and rigidly attached to it, is the remaining part, C, of the plunger-barrel, the lower end of which is fashioned as the usual conical-shaped 60 nose.

In the frame A, near its upper end, is jour- naled a horizontal shaft, b , upon which, be- 65 tween the shaft-bearings, is securely mounted a pulley, D, so that the revolution of the pul- ley will rotate the shaft.

E E' represent reversely-curved yokes, which are connected by a rod, c . The arms of the yoke E extend on opposite sides of the frame A and their extremities are bored to permit 70 the passage through them loosely of the oppo- site ends of the shaft b , just outside of its bear- ings, as shown in Fig. 1. Within the yoke E' is journaled a shaft carrying a pulley, d , said pulleys d and D being operated together 75 by a connecting belt. Power coming from any suitable source may be applied to the pul- ley d , and thus to the machine. This arrange- 80 ment permits an easy change of position in the machine during its operation without the danger of disarranging the parts which apply the driving-power.

On one end of the shaft b is secured a pin- 85 ion, e , which meshes with a gear-wheel, F, whose spindle is journaled in one of the side uprights of frame A. This gear F engages a pinion, f , on the end of a horizontal shaft, g , whose bearings are formed in a horizontal casting, G', situated within the lower portion 90 of the frame A and above the casting B. The shaft g carries a rigidly-attached segment-gear, G, which works within a space in the casting G' between the two shaft-bearings. (See Fig. 4.)

The plunger-rod H occupies a vertical pas- 95 sage-way through the parts B and C, the upper extremity of said plunger emerging from the part B, and being preferably provided with a rounded terminal knob, i . A portion of the passage which receives the plunger is formed as an elongated chamber, H', which contains a spiral spring, I, that is coiled closely about 100

the plunger and is tensioned between the upper wall of the chamber and a collar secured to the plunger and resting normally on the bottom of the chamber. Below the chamber 5 H' the plunger is formed only as a small cylindrical rod, and the passage which contains it is correspondingly decreased in size.

It will be readily seen that if the plunger H be raised by any means the spring I will be 10 compressed, and then, if the elevating agent be suddenly removed, the expansion of the spring will drive the plunger downward. The spring I is of such a degree of resiliency that the descent of the plunger will be of sufficient 15 power to drive the tack that may be in its path.

The plunger H is provided along its rear side with a series of teeth, k, which form a 20 rack-bar, that lies in the same vertical plane with the segment G. The plunger is normally situated so that the upper tooth of the rack-bar will be just far enough from the gear G to escape being engaged thereby during the revolutions of the segment, and yet the segment 25 and rack-bar are in such proximity that if the plunger is raised slightly the engagement between the segment and the rack will take place. This engagement will result in elevating the plunger, and the elevation will 30 continue until the last tooth of the segment has been disengaged from the rack, when the resilient action of the compressed spring I will force down the plunger.

It is obvious that various mechanical devices 35 may be employed for the purpose of raising the plunger-rod, so that the rack may come into engagement with the segment. In the drawings (see Fig. 2) there is shown a crank-lever, J, which is pivoted to a projection on the casting B. One end of the lever J rests beneath a lug, k', on the plunger. If, now, the lever J be moved from the position shown in full lines to the position shown in dotted lines, the plunger will be raised sufficiently 40 to bring it under the action of the segment-gear. At each revolution of the segment the plunger will be elevated and subsequently brought down by the action of the spring and a tack driven. The machine is thus 45 under the easy control of the operator, who has simply to manipulate the lever J, pressing it toward the plunger-barrel when he desires to drive a tack and relaxing his hold thereon after the driving is concluded, and to suit the varied movements of the machine.

Evidently by continuing the pressure upon the lever any number of tacks may be driven successively where the nature of the work will permit it.

60 It now remains to describe the manner in which the tacks are automatically placed beneath the plunger one by one in succession.

K indicates the inclined chute or raceway, which is secured at its lower end to the plunger-barrel. This raceway is provided with a longitudinal groove that is filled with tacks, and which opens into a tubular orifice that ex-

tends vertically through the lowermost portion of the raceway metal.

The operation of filling the raceway may be 70 performed by any suitable devices, one of which will be hereinafter described.

The casting C is provided with an inclined conical-shaped channel, L, which opens at its upper end just below the lower end of the raceway and coincident with the tubular orifice above mentioned, and the lower end of which channel L enters the circular passage, wherein the part h of the plunger-rod operates. Thus a tack coming down the channel 80 L will be delivered into the plunger-passage in advance of the rod, provided the rod is elevated, and if not elevated the tack will rest at the point where the two passages meet until the rod h rises past that point, when it will 85 slip down to the lower end of the nose. It therefore becomes necessary to devise means for transferring the tacks individually from the raceway K to the channel L. In order to accomplish this we provide a perpendicular 90 rod, M, which is journaled in the projection l on the plunger-barrel, so as to be horizontally rotative. Collars m m are affixed to the rod above and below the bearing l, and the lower end of the rod enters the tubular orifice at the 95 base of the raceway-groove, while the upper end is provided with a cam, N, which is shaped as a convoluted wing. This cam is rigidly attached to the rod M by means of a set-screw or other suitable devices, or it may 100 be made integral with the rod. The head of the plunger-rod is situated directly below this wing-shaped cam in such a manner that during the ascent of the plunger its head will bear against the under face of the cam, thereby moving it and rotating the rod M. A properly-tensioned spring, P, on the rod M acts to return the cam and rod to their first position after the plunger has moved downward out of contact with the cam. Further, the lower 105 portion of the rod M is cut away, as shown, leaving a horizontal plate, n, which lies directly at the extremity of the raceway-groove. (See Fig. 6.) The plate n is notched at o, Fig. 8, the notch being only large enough to 110 receive the body of an ordinary tack.

It will be further noted as an important feature that the plate n is situated eccentrically within the tubular orifice at the base of the raceway—that is to say, it is so situated 120 within the orifice as to lie close to the end of the raceway-groove, while there is more or less space between it and a part or the whole of the remainder of the wall of said orifice. (See Fig. 3.)

Above the plate n the rod M is vertically slotted to allow a swinging arm, O, to be pivoted therein, said arm being formed with a projecting foot, p, which extends into proximity to the notch o, and also with a vertical 130 downward projection, r, which enters an irregular cam-shaped groove, u, which partially surrounds the rod M, and is formed in a plate provided for the purpose, or is provided in

any other convenient way. When the rod M has been partially rotated by the action of the plunger-rod, the notch o in the plate n will register with the raceway-groove, and a tack will 5 slip from the groove and be lodged therein. The arm O will also be so governed by the movement of its projection r within the irregular groove u that the foot p will be behind the notch o, as shown in Fig. 6. Now, 10 when the rod M flies back under the tension of spring P, the tack carried by the plate n will be moved to a point where there is a slight distance between the wall of the tubular orifice and the eccentrically-located rod, and at the 15 same time the movement of the arm O under the action of the irregular groove will be such as to throw the foot against the tack and push it from the plate so that it will fall into the channel L. It will thus be seen that at each 20 partial return rotation of the rod M a tack will be shifted from its position in the raceway to the channel L, and thus to the nose in advance of the plunger.

The raceway or chute which feeds the tacks 25 to the plunger may obviously be filled in various ways. We have represented in our drawings one plan of mechanism for accomplishing this result. It comprises a hollow rotary drum, Q, mounted on suitable supports, 30 which are connected rigidly to the framework that supports the tack-driving mechanism. In the drawings, T denotes a standard secured to the plate U, fastened to the plunger-barrel. A horizontal connection, T', extends 35 between standard T and another standard, T'', between which standards the drum Q is situated. Through one side of the drum passes the raceway. The drum is actuated by any convenient driving-power. Its interior is provided with a series of plates or partial partitions, v, which form buckets. A part of these buckets are filled with tacks, the wall of the drum being furnished with a door, w, for the easy admission of the tacks to the interior of 40 the drum. The rapid revolution of the drum will cause the tacks within to fly about in great confusion, and enough will be caught by the raceway to keep it constantly full.

Inasmuch as from the foregoing description 45 of the construction and disposition of the several parts of our improved tack-driving machine the operation of the entire machine will be clearly evident to those skilled in the art to which this invention appertains, there need be but little further said on that score. The fact that the machine is hung from above 50 enables the operator to swing it with ease from point to point of the work.

A suitable handle, S, is secured to the machine to assist in its manipulation. The rack-bar on the plunger is normally out of engagement with the segment-gear, so that the power-supplying devices are kept constantly running, while the tack-driving mechanism is 55 maintained in a state of rest, except when the operator causes the plunger-rod to be brought under the action of the segment. Each time

the plunger is raised by the segment the head of the plunger acts upon the cam carried by the horizontally-rotative tack-shifter, and a tack is taken from the raceway and transferred to a position in the barrel, whence it passes in advance of the plunger, where the latter will strike it in its descent.

The parts of the machine are so related and 70 adjusted for operation, as hereinabove set forth, that when the plunger is in its elevated position the plate n will be in the position where it receives a tack from the chute. Consequently, when the plunger descends, this tack 80 on the plate n will be thrown into the channel L; but when it reaches the end of this channel it will be barred by the rod h from at once entering the nose in advance of the said rod. It will therefore rest against the rod h until at 85 the next elevation of the plunger this barrier will be removed and the tack allowed to drop to the extremity of the nose, with its point resting upon the work at the exact spot where it is to be driven. Thus it will be clearly seen 90 that each time the plunger begins its descent—that is to say, each time it passes below the cam—that tack is thrown into the barrel which will be driven at the next descent of the plunger, and that tack is driven which was dropped 95 into the barrel at the previous descent of the plunger.

Having thus described our invention, what we claim as new, and desire to secure by Letters Patent, is—

100

1. In a tack-driving machine, the combination of a plunger-barrel, a spring-actuated plunger within said barrel provided with a rack-bar, and a rotating segment-gear arranged, substantially as specified, so that the plunger may be engaged thereby when desired, and thus intermittently elevated, substantially as described.

2. In a tack-driving machine, the combination of the skeleton frame, the driving and the segment-carrying shafts journaled in suitable bearings and geared together, the plunger-barrel, the spring-actuated plunger having a vertical series of teeth, said plunger being arranged, substantially as set forth, so as to be 110 intermittently elevated by the segment-gear, and suitable devices for thus situating the plunger, substantially as described.

3. The combination, with the raceway and the channeled plunger-barrel, of a horizontally-rotative rod suitably formed to receive a tack and provided with a swinging foot to push the tack therefrom, together with mechanism, substantially as specified, for rotating said rod in both directions, and likewise devices for operating the swinging foot, all arranged substantially as and for the purposes described.

4. The combination, with the raceway and the plunger-barrel having an auxiliary inclined channel communicating with the main 120 passage, of the horizontally-rotative tack-shifter having a notched plate, which receives the tack, and a pivoted foot for pushing off the tack into the inclined passage at the proper

instant, together with a cam-groove for actuating the pivoted foot and suitable mechanism for imparting motion to the said tack-shifter relatively to the movements of the plunger, 5 and also for automatically replacing the shifter in its normal position, substantially as described.

5. In a tack-driving machine, the combination of the plunger-barrel having a main passage and an auxiliary inclined passage, the spring-actuated plunger formed with a toothed rack, the rotating segment-gear for elevating said plunger, and the horizontally-rotative tack-shifter provided with a wing-cam arranged to be operated by the plunger-head at each elevation thereof, substantially as described.

6. The combination of the upper frame, the horizontal driving-shaft journaled therein and 20 operated by suitable power, the segment-gear carried by a suitably-journaled horizontal shaft, said driving and segment-carrying shafts being geared together, as shown, the plunger-barrel having a main and an auxiliary inclined 25 passage, the spring-actuated plunger provided with a rack-bar, the horizontally-rotative tack-shifter having at its upper end a wing-cam to be acted on by the plunger-head, and having also a notched plate to carry the tack and a 30 pivoted foot to throw off the tack, the spring coiled about said tack-shifter for returning the same to its normal position, and suitable means,

as a lever-handle, for raising the plunger so that its toothed portion may be engaged by the segment-gear, substantially as described. 35

7. The combination, with the raceway, the plunger-barrel having a main and an inclined auxiliary passage, and the plunger-rod, of the horizontally-rotative tack-shifting rod formed with a notched plate to receive the tack, and 40 provided with a pivoted arm having a projecting foot for throwing the tack off the plate, and a downward-extending lug, and provided, also, with a wing-cam, whereby the rod is rotated under the action of the plunger-head, 45 the spring for returning the rod to its normal place, and the cam-shaped groove which receives the lug on the arm, and thus governs the action of the foot, substantially as described.

8. In a tack-driving machine, the herein-described device for transferring the tacks individually from the raceway to the plunger-barrel, consisting of the rod M, having a wing-cam, N, and plate n, with notch o, the arm O, pivoted to said rod and having foot p and lug r, the irregular cam-groove u, and the spring P, substantially as described. 50
